UNITED STATES PATENT OFFICE.

GUSTAV ERDBRÜGGER, OF BAD OEYNHAUSEN, GERMANY, ASSIGNOR, BY MESNE ASSIGNMENTS, TO ALBERT WEBER, OF NEW YORK, N. Y.

SUCTION GAS PLANT.

Application filed September 9, 1922. Serial No. 587,209.

To all whom it may concern:

Be it known that I, GUSTAV ERDBRÜGGER, a citizen of the German Republic, residing at Bad Oeynhausen, Germany, have invented certain new and useful Improvements in Suction Gas Plants, of which the following is a specification.

In suction gas plants for the production of power gas the gasification of bituminous fuel can be carried through only if the plants are fitted with a generator.

In generators using anthracite coal or coke a mixture of air and steam is injected into the generator below the grate to be decomposed by the coke heated to incandescence and drawn off as power gas by the suction of the engine.

In the gasification of bituminous fuel the process is reversed. The jet of gasifying air is injected above the layer of coal and the power gas is drawn off either directly below or above the grate or directly from the incandescent layer.

By this method the inconvenient tar vapors and the gases from distillation are transformed into combustible gases suitable for the working of the internal combustion engine.

This invention relates to a suction gas plant for internal combustion engines as well as for reheating and tempering furnaces in which plant without any change of construction, but merely on adjustment of a valve, either bituminous or non-bituminous fuels can be gasified.

This result is obtained by injecting the jet of steam and air into the gas generator below the grate if anthracite, coke, or charcoal is used and the gas is drawn off at the top whilst if brown coal, briquettes, peat, wood, or the like are used the air jet is injected above the layer of fuel and the gas is drawn off immediately below or above the grate or even directly from the fuel.

The improved suction plant according to the invention could further be used as a generator for motor driven cars, the generator being of small dimension and little weight and adapted to be operated from the motor-man's seat.

In order to make my invention clear, the same is more or less diagrammatically illustrated in the accompanying drawings show-

ing one embodiment of my invention and in which:

Fig. 1 is a vertical section of the improved gas generator for the gasification of anthracite, coke, or charcoal and it is a section on line A—B of Fig. 3.

Fig. 2 shows the same gas generator for the gasification of brown coal, briquettes, peat, wood or the like and is a section on line C—D of Fig. 4.

Fig. 3 is a plan view of the improved gas generator.

Fig. 4 is a horizontal section on line J—K of Fig. 2.

Fig. 5 is a section on line E—F of Fig. 3, and

Fig. 6 is a section on line G—H of Fig. 3.

Fig. 6^a is an enlarged vertical section similar to Fig. 1.

Referring to Figs. 1 and 6^a, *c* denotes the gas generating chamber, which in the present case is cylindrical in shape and is made up of refractory bricks, as usual. The same is provided at its bottom with a grate *b* and is arranged eccentrically in a casing *C* (Figs. 3 and 4). The space in the casing around and below the chamber *c* is partitioned off as best shown in Figs. 4 and 6^a to form two adjacent chambers *i*, *L* of substantially crescent shaped cross section, of which one, say *i*, serves as a gas purifying chamber and the other *L*, as a gas drying chamber. Between these chambers and the gas generating chamber are formed intermediate chambers *o*, *p*, which are open on top to the atmosphere and which are adapted to communicate with one another through lateral passages (not shown). Below the chambers *i*, *L* a gas collecting chamber *n* is formed. At the sides of the gas generating chamber flues *e*, *h* and *v* are provided of which flues *h* and *v* are arranged adjacent to one another at one side of the chamber and flue *e* at the opposite side of the latter. On the open top of the gas generating chamber *c* around the charge opening or dome *c'* of the latter is mounted an annular cup *f* which is adapted to serve as a steam generator and to have a water pipe connection (not shown). Leading from this cup is a tube *q*² from which are branched off two tubes *q* and *q'*, the tube *q* terminating in the flue *e* and the tube

 5 *q'* extending through the dome and terminating in the upper part of the chamber *c*. The flue *e* at its bottom communicates through a passage *e'* with the ash pit *t* below the grate *b*. The tube *q*² is connected to the tubes *q* and *q'* through a two way cock or valve *r*, so that the steam generating cup *f* may be brought into communication either with the ash pit through tube *q'*, 10 flue *e* and passage *e'* or directly with the chamber *c* through the tube *q*. Leading from the top of the chamber *c* are two tubes, a tube *d'* controlled by a valve *d* and leading into the atmosphere and a tube *s* leading 15 through branches *h'*, *v'* into the flues *h* and *v* respectively and connected to said branches by a two way cock or valve *w*. The flue *h* at its bottom is extended below the ash pit and communicates through passages 20 *h*² and *h*³ with the purifying chamber *i*. The flue *v* communicates at its bottom with the ash pit *t* through a passage *u* (Fig. 6^a). Leading from the top of the purifying chamber *i* into the adjacent chamber *L* is a 25 pipe *k* which terminates near the bottom of said chamber *L*. Leading from a point near the top of and extending vertically through said drying chamber *L* is a pipe which projects into the gas collecting chamber *n* (Fig. 30 6^a). The latter has a discharge passage *n'* from which the generated gases may in a suitable manner be conveyed to a motor or the like. *a* denotes a suitable hand pump connected to the flue *e* and by means of 35 which starting air can be blown under the grate *b* of the chamber *c* for the starting of the generator. The air blown in by the pump *a* is transformed into the chamber *c* into power gas and other gases which are allowed 40 to escape into the atmosphere through the valve *d*.

One object of arranging the intermediate chambers *o* and *p* between the heated gas generator *c* and the purifier chambers *i* and *L* is to permit the air entering the gas generator to be preheated before passing into the cup *f*. Another object thereof is to insulate the chambers *i*, *L*, from the walls *c*² of the gas generating chamber *c*, so as to 45 prevent the gases flowing therethrough from being heated.

The operation of the generator is as follows:

When anthracite fuel is used, steam has to 55 be produced by feeding water in a suitable manner into the cup *f* to produce the preliminary heating of the gasified air. Starting air is blown under the grate *b* by means of the hand pump *a* and the gases formed permitted to escape through the reversing valve *d*. When the engine is to be started the valve *d* and the air pump *a* are closed and the air to be gasified enters the evaporation cup *f* from the chamber *o* through pipe *g*. 60 65 The cock *r* having previously been corre-

spondingly adjusted, permits the air to pass from the cup *f* into the flue *e* through which it enters the ash pit *t* and thence, (the valve *w* having been closed to the flue *v*), rises through the grate *b* into the generating 70 chamber *c*. The power gas produced in the latter passes out through the tube *s*, valve *w* into the flue *h* and through the latter into the purifier chamber *i*. From the latter it passes through the pipe *k* into the drying 75 chamber *L* and thence through the pipe *m* into the gas collector *n* from which it may be supplied to the engine.

For the gasification of bituminous fuel, the water contained in the fuel is sufficient 80 to produce the desired quantity of steam and therefore no additional water need be dropped into the evaporation cup *f*. In this case, the cock *r* having been closed to the flue *e*, the air passes from above into the generating chamber *c* from the evaporation cup *f* through the pipe *q*, and as the cock *w* closes the pipe *s*, the gas produced in the chamber *c* will now pass downwardly 85 through the grate *b* into the ash pit *t*, thence through the port *u* into the flue *v* and thence through the valve *w*, flue *h* into the purifier *i* and from the latter as in the first case through the pipe *k* into the drying chamber *L* then finally through pipe *m* into the 90 collecting chamber *n*.

The two cocks *r* and *w* may be connected to one another by a rod *x*, so that by turning a handle *y* an angle of 90° the cocks *r* and *w* will be adjusted for the generation 100 of gas from one to another kind of fuel to be used.

I claim:

1. In a suction gas plant, a gas generating chamber having a grate, a steam generating cup, an air chamber communicating with said cup, valve controlled means for controlling communication of the evaporation cup either with the space below the grate or the top of said gas generating chamber, a gas purifying chamber, valve controlled means for controlling communication of the gas generating chamber with the purifying chamber either from below or above the grate thereof and a collecting chamber communicating with said purifying chamber. 105 110 115

2. In a suction gas plant, a gas generating chamber having a grate, a steam generator cup, an air chamber communicating with said cup, valve controlled means for controlling communication of the evaporation cup with the space below the grate or the top of said generating chamber, a gas purifying chamber, valve controlled means for controlling communication of the gas generating chamber with the purifying chamber either from below or above the grate thereof and a collecting chamber communicating with said purifying chamber, said air chamber being arranged between said generating 120 125 130 135

chamber and purifying chamber to act as a preheater.

3. In a suction gas plant, a gas generating chamber having a grate, a steam generator cup, an air chamber communicating with said cup, valve controlled means for controlling communication of the evaporation cup either with the space below the grate or the top of said generating chamber, a gas purifying chamber, valve controlled means for controlling communication of the gas generating chamber either with the purifying chamber from below or above the

grate thereof and a collecting chamber communicating with said purifying chamber, the valves of said means being operatively connected together to permit by a single operation the change of the direction or flow of the air and gas. 15

In testimony whereof I affix my signature in presence of two witnesses. 20
